W. H. Page

United States Patent Office.

WILLIAM H. PAGE, OF NORWICH, CONNECTICUT, ASSIGNOR TO WM. H. PAGE & CO., OF SAME PLACE.

Design No. 4,283, dated August 9, 1870.

DESIGN FOR TYPE.

The Schedule referred to in these Letters Patent and making part of the same.

I, WILLIAM H. PAGE, of Norwich, in the county of New London, State of Connecticut, have invented or produced a new and original Design for an Alphabet of Letters for printing purposes, styled "Etruscan."

My design is for an alphabet of letters, as shown and described by the accompanying impressions.

The letters may be printed as shown, or in two

colors, as represented in the two C's shown on the same sheet.

I claim as my invention—

The design for letters, as shown.

WM. H. PAGE.

Witnesses:

JAMES D. MOWRY,

CHARLES C. FULLER.
